J. Galvin.

Windlass.

Patented Nov. 6, 1810.

Fig. 2.

John Galvin

Solders Patent, date 8 November 6th 1880.

The Schedule is referred to in this Seller's Patent and making part of this containing a description in the words of the said John Galvin himself, of his improvement in the Windlass and Capstan.

This Machine is intended to supersede the common mode of weighing Anchors, it has two different powers, either of which may be employed as circumstances should require.

On each end of the Windlass place a cog-wheel of Iron, say about 40 inches diameter, above each place another cog-wheel of Iron, say 13 inches to $\frac{3}{5}$ or one third of the first. This power is as two to six hand spikes or two men can haul as much as six men and spikes by the usual method, as it is calculated for all common uses.

A second power may be given to it by having also on the upper axis a smaller cog-wheel, say 10 inches or $\frac{1}{2}$ of the main cog-wheel this may be used in extraordinary occasions when the anchor has a heavy hold in the ground, or when breaking fresh and wanting to haul a head, or get under weigh, it is as two to eight hand spikes, and by double or triple main the power is increased to a four fold or triple proportion, it is also of the utmost importance in case of getting a ground as the power may be carried to any point the machine or cord, is capable of sustaining.

The axis on which the smaller cog-wheels are placed, is turned by a vertical drum head, similar to the common Capstan, the bars are secured by a swivel and may be in a number proportioned to the size of the vessel, say from 8 to 12. The windlass is mounted drum back or toing, what is gained by a ratchet wheel and rolls the same as in common use.

N.B. The ruddip screw may be substituted for the propelling cog-wheels which it is in and required to make a part of the patent tho' it is not shown in the accompanying drawings. A Capstan may be made on the same principles, only operating horizontally instead of vertically.
